DESIGN FOR A CURTAIN

Gustave F. Erhard, Scranton, Pa., assignor to The Scranton Lace Company, Scranton, Pa., a corporation of Pennsylvania

Application October 15, 1937, Serial No. 72,186

Term of patent 3½ years

To all whom it may concern:

Be it known that I, Gustave F. Erhard, a citizen of the United States, residing at Scranton, county of Lackawanna, and State of Pennsylvania, have invented a new, original, and ornamental Design for a Curtain, of which the following is a specification, reference being had to the accompanying drawing, forming part thereof, wherein—

The figure is a plan view of approximately one-half of a curtain showing my new design, the weave being continued laterally, in continua-

tion of the design as shown, for the full width of the curtain; and the weave also being continued between the upper and lower portions, shown separated in the drawing, to produce additional rows corresponding to element A spaced apart by additional rows corresponding to element B, for the full length of the curtain.

I claim:

The ornamental design for a curtain substantially as shown and described.

GUSTAVE F. ERHARD.
